UNITED STATES PATENT OFFICE.

JOSEPH HIGGINS, OF COLLEBRAN, ALABAMA.

FOLDING RECEPACLE.

1,277,585.

Specification of Letters Patent.

Patented Sept. 3, 1918.

Application filed June 6, 1916. Serial No. 101,977. Renewed June 6, 1918. Serial No. 238,609.

To all whom it may concern:

Be it known that I, JOSEPH HIGGINS, a citizen of the United States, residing at Collbran, in the county of Dekalb and State 5 of Alabama, have invented certain new and useful Improvements in Folding Receptacles, of which the following is a specification.

This invention relates to improvements in 10 foldable or collapsible receptacles or crates, and has for one of its objects to improve the construction and increase the efficiency and utility of devices of this character.

With this and other objects in view, the 15 invention consists in certain novel features of construction, as hereinafter shown and described and then specifically pointed out in the claims; and in the drawings illustrative of the preferred embodiment of the invention—

Figure 1 is a side elevation of the improved device in open or operative position;

Fig. 2 is a longitudinal sectional elevation 25 with parts arranged as shown in Fig. 1;

Fig. 3 is a longitudinal sectional elevation with the parts in collapsed or folded position;

Fig. 4 is an end elevation with the parts arranged as shown in Fig. 1;

Fig. 5 is a transverse elevation on the line 30 5—5 of Fig. 2;

Fig. 6 is a detail view illustrating the manner of holding the yieldable locking member in open or detached position;

Fig. 7 is a transverse section on the line 35 7—7 of Fig. 3;

Fig. 8 is a view similar to Fig. 7 illustrating a modification in the construction.

Corresponding and like parts are referred 40 to in the following description and indicated in all the views of the drawings by the same reference characters.

The improved device comprises a bottom member 10, lower side members 11—12 rigidly connected to the bottom 10 and end plates 13—14, the latter terminating a short distance above the upper line of the rigid lower side members 11—12 and extending at 45 their lower ends below the lower line of the bottom 10 with their lower ends directed inwardly to form cleats or supports 15—16, the latter being spaced away from the bottom 10, as shown.

Hingedly united at 17 to the upper edge 50 of the lower rigid side member 11 is an upper side member 18, while a similar upper

side member 19 is hingedly united at 20 to the upper edge of the lower rigid side member 12, the members 18—19 being thus foldable inwardly into transverse alinement 60 with each other, as shown in Fig. 7.

Mounted upon the bottom member 10 at its ends and next to the plates 13—14 are spacer members 21—22, and pivoted at 23—23' between the stationary side members 11—12 are end members 24—25 which bear against the inner faces of the plates 13—14 when in vertical position, as shown in Fig. 2, the end members being thus foldable inwardly into parallel relation to the bottom 65 10 and in alinement with each other, as shown in Fig. 3. If required a division member or partition 26 may be employed and pivoted at 27 between the members 11—12 and foldable upon the bottom 70 10 when the receptacle is collapsed, as shown in Fig. 3. The pivots 23—23' and 27 are preferably rods extending entirely through the members 11—12 and likewise through the end members 24—25 and the division mem- 75 ber 26.

The top member of the receptacle is represented at 28 and bears upon the upper edges of the members 24, 25 and 26 and likewise upon the upper edges of the upper side 80 members 18—19, as shown in Figs. 1 and 2, when the receptacle is in open position. The members 24, 25 and 27 are provided respectively with dowel pins 29, 30 and 31, as shown in Fig. 1, to enter suitable sockets in 85 the top member 28, and hold the latter from lateral displacement.

When the receptacle is collapsed the top 28 is disposed beneath the bottom 10 and supported at the ends by the inwardly directed cleat members 16—17, as shown in 90 Figs. 3, 7 and 8.

Mounted upon the ends 24—25 are bearings 32 arranged in pairs spaced apart, and mounted for rotation through each set of the 95 bearings is a rod 33 extending at its outer end beyond the outer walls of the receptacle and directed at right angles to the body of the rod, as shown at 34, to bear over the adjacent portions of the upper side members 100 18—19. At its center the rod 33 is bent into a loop 35 with the outer portion of the loop bent at right angles, as shown at 36, and in parallel relation to the terminals 34, the portion 105 36 of the loop bearing over the adjacent portion of the top 28 when the receptacle is in open position, as shown. A spring 37

is applied to the rod 33 and operating to maintain the portions 34-36 yieldably in the position shown in Figs. 1 and 2. By this arrangement it will be obvious that the rod, together with its folding portions 34-36, operates to hold the members of a crate locked in open position.

Connected to each of the end members 24-25 is a bearing 38, and mounted to 10 swing in each of these bearings is a holding loop 39 adapted to engage the loop portion 35-36 of the rod and hold the members 34-36 out of engagement with the top 28 and the side members 18-19, as shown in 15 Fig. 6, to enable the top to be readily attached or removed. A suitable catch device, represented conventionally at 40, is utilized to hold the members 18-19 when in collapsed position, as shown in Figs. 7 and 8. 20 By this arrangement it will be obvious that an effectual collapsible or folding crate or receptacle is produced which may be extended for use, as shown in Figs. 1, 2, 4 and 5, and locked in its open position, or collapsed, as shown in Figs. 3 and 7, to occupy less space for shipment or storage.

In Fig. 8 a slight modification in the construction is shown consisting in forming the side members 11-12 of less height than 30 shown in Figs. 1 to 7, and arranging the parts 18-19 to overlap instead of being arranged in transverse alinement. When the modified structure shown in Fig. 8 is employed the part 12 will exceed in height the 35 part 11 a distance equal to the thickness of the member 18, so that the members 18-19 will fold into close parallel relation, as shown. By this latter arrangement the device occupies less space when folded, and 40 may be employed under certain conditions if required.

The main portions of the device including the bottom, sides, ends and top and the partition 26 will preferably be of wood, while the 45 remaining parts will be of metal of suitable strength, and preferably galvanized or otherwise protected from corrosion. The lower stationary side members 11-12 are preferably provided with openings 41 to 50 receive the terminals 34 when the end members 24-25 are collapsed or folded, as shown in Fig. 3.

Having thus described the invention, what is claimed as new is:

55 1. A foldable receptacle comprising a bottom, and lower side and end portions rigidly united, upper end and upper side portions

mounted to fold substantially into parallel relation to the bottom, supporting cleats extending beneath the bottom and spaced 60 therefrom, and a top adapted to engage the sides and ends when in distended position and to be supported beneath the bottom by said cleats when the receptacle is collapsed.

2. A foldable receptacle including a bottom, sides and ends foldable substantially into parallel relation to the bottom, supporting cleats extending beneath the bottom and spaced therefrom, and a top adapted to engage the sides and ends when in distended 70 position and to be supported beneath the bottom by said cleats when the receptacle is collapsed.

3. A foldable receptacle including a bottom, sides and ends foldable substantially 75 into parallel relation to the bottom, supporting plates bearing against the ends and terminating in cleat devices, and a top adapted to engage the sides and ends when in distended position and to be supported by 80 the cleat portions of said plates when the receptacle is collapsed.

4. A foldable receptacle including a bottom, sides and ends foldable into parallel relation, a top engaging the sides and ends when distended, and rods mounted for longitudinal rotation upon said ends and each formed with lateral terminals to engage over the outer faces of the sides and an intermediate loop to engage over the top. 90

5. A foldable receptacle including a bottom, sides and ends foldable into parallel relation, a top engaging the sides and ends when distended, rods mounted for rotation upon said ends and each formed with lateral 95 terminals to engage the sides and a loop to engage the top, and springs operating respectively to hold said rods yieldably in locked relation to the sides and top.

6. A foldable receptacle including a bottom, sides and ends foldable into parallel 100 relation, a top engaging the sides and ends when distended, rods mounted for rotation upon said ends and each formed with lateral terminals to engage the sides and a loop to 105 engage the top, springs operating respectively to hold the rods yieldably in locked relation to the sides and top, and means for holding said rod with its terminals and loop disengaged from the sides and top against 110 the resistance of said springs.

In testimony whereof I affix my signature.

JOSEPH HIGGINS. [L.S.]
